UNITED STATES PATENT OFFICE.

PETER J. NAGLE, OF ROCHESTER, NEW YORK, ASSIGNOR TO FLOWER CITY SPECIALTY COMPANY, OF ROCHESTER, NEW YORK, A CORPORATION OF NEW YORK.

DISPLAY RECEPTACLE.

Application filed October 12, 1920. Serial No. 416,434.

To all whom it may concern:

Be it known that I, PETER J. NAGLE, a citizen of the United States, and resident of Rochester, in the county of Monroe and 5 State of New York, have invented certain new and useful Improvements in Display Receptacles, of which the following is a specification.

The present invention relates to display 10 receptacles and more particularly to the type having an inner display cover which will display the contents of the receptacle when the outer cover is open and yet will prevent the surreptitious removal of the 15 contents of the receptacle, an object of this invention being to provide an inner display cover which will be inexpensive to manufacture and durable in use.

To this and other ends, the invention consists of certain parts and combinations of parts all of which will be hereinafter described, the novel features being pointed out in the appended claims.

In the drawings:—

25 Fig. 1 is a plan view of a receptacle constructed in accordance with this invention, the outside cover being removed;

Fig. 2 is a view of the under side of the display cover showing the hinging flap bent 30 to the plane of the display cover, parts being broken away and one of the side extensions of the upper layer being shown in dotted lines in the plane of the upper layer;

Fig. 3 is an enlarged section on the line 35 3—3, Fig. 1;

Fig. 4 shows the blank from which the display cover is made;

Fig. 5 is a vertical section through the receptacle;

40 Fig. 6 is a vertical section at right angles to the section shown in Fig. 5; and

Fig. 7 is a section on the line 7—7, Fig. 1.

Referring more particularly to the drawings, 1 indicates the body of the receptacle 45 which, in this instance, is of rectangular formation with vertical front, rear and side walls. The outside cover 2 with a surrounding flange 3 is hinged at 4 to the exterior of the rear wall of the receptacle and is 50 movable on the receptacle to cover and uncover the latter.

The display cover which forms a novel part of this invention embodies an upper layer 5 and a lower layer 6. These two 55 layers are preferably formed from a single

piece of cardboard scored at 7 so that the layer 6 may be folded under the layer 5, both layers being provided with registering openings 8. The layer 6, in this instance, is narrower than the layer 5, and the latter 60 preferably has secured to it along opposite edges, two strips 9 which, in this instance, are formed from extensions on the sheet blank on the opposite edges of the layer 5, said extensions being bent or turned inwardly on the under side of the layer 5 and adhesively secured to such under side. When the under layer 6 is folded under the layer 5, its edges abut the edges of the strips 9. A thin sheet 10 may be employed to 65 cover the under face of the layer 6 and the under faces of the strips 9 so that a pocket is provided between the layers 5 and 6, opening at one edge of said layers. In this 70 pocket a transparent sheet 11 of celluloid or other zylonite material is introduced. Owing to the fact that the strips 9 are provided at opposite edges of the layer 6, the 75 edges of these strips form abutments for the edges of the transparent sheet 11 and thus 80 make it possible to use a sheet narrower in width than the display cover and, at the same time obtaining a display cover which 85 is materially strengthened, these strips acting as reinforcing means for the upper layer and preventing the distortion of the latter.

The display cover is preferably hinged to the front wall of the receptacle 1, and to this end has a hinging strip 12 which is preferably formed in one piece with the upper layer at the edge of the latter opposite the edge from which the lower layer projects. This strip is adhesively secured to the inner face of the front wall of the receptacle 1, its lower edge resting upon the bottom of the receptacle, thus defining the position at 90 which the display cover shall lie in the receptacle. This position is further defined by ledges 13 provided on the side and rear walls of the receptacle, these ledges being 95 formed by strips 14 adhesively secured to said walls. In order to prevent the accidental displacement of the transparent sheet 11 from the pocket between the layers 5 and 6, a closure strip 15 may be adhesively secured to the hinging strip 12 and the under face of the layer 6 adjacent the mouth of the pocket.

A display receptacle constructed in accordance with this invention permits the use 100 105 110

of a thin transparent sheet of material such as celluloid for closing the display openings. The pocket in which this transparent or celluloid sheet is received is economically formed from cardboard in a manner to require a minimum amount of the transparent material, while at the same time preventing any loose movement of the material in the pocket. The position of the material in the pocket is defined by two strips on opposite sides of the lower layer and these strips act also to strengthen the display cover transversely to prevent any bulging of the latter.

What I claim as my invention and desire to secure by Letters Patent is:

1. A display cover comprising two layers, one superimposed upon the other and said layers having registering openings, strips arranged along opposite edges of one of the

layers and adhesively secured to one side of the other layer, a transparent sheet loosely arranged between the layers and between the strips, and means for securing the two layers together so that the transparent sheet may be readily inserted between or removed from a position between the layers.

2. A display cover comprising a single piece of sheet material bent to provide two superimposed layers connected to each other at one edge, strips adhesively secured to one face of one of the layers along opposite edges of the other layer the layers having registering openings, a thin sheet adhesively secured to the strips and to the layer situated between the strips, and a transparent sheet arranged between the layers and between the strips.

PETER J. NAGLE.
